STACK LEG TABLE

Roy Bruce Lindvall, St. Peter, Minn., assignor to Beam Furniture, Inc., St. Peter, Minn.

Filed July 17, 1972, Ser. No. 272,642

Term of patent 14 years

Int. Cl. D6—03

U.S. Cl. D6—177

FIG. 1 is a perspective view thereof;
FIG. 2 is a side elevational view thereof;
FIG. 3 is a front elevational view thereof which is the same as the back elevational view thereof;
FIG. 4 is a top elevational view thereof; and
FIG. 5 is a bottom elevational view thereof.
I claim:

The ornamental design for a stack leg table, as shown.
